SECTIONAL COLLAPSIBLE PRESSING BOARD

Josephine S. Buchanan, Sharon, Conn.

Application June 28, 1950, Serial No. 170,837

2 Claims. (Cl. 38—138)

1

This invention relates to pressing boards and is more particularly directed to pressing boards which may be collapsed for convenience in carrying or storing when they are not in use.

In the small modern apartment or hotel room, in which space is very limited, it is desirable to dispense with the usual rigid pressing or ironing board and its unstable supporting leg structure, and to provide a pressing surface or board which is collapsible and which may be conveniently stored or readily carried when traveling. Therefore, it is an important object of this invention to provide a device which may be readily collapsed by telescoping the members, forming the pressing surface, so that they occupy a minimum of space and which, when in the open or extended position, will provide a rigid pressing surface.

Another object is to provide a telescoping ironing or pressing board which may be used as a container for a traveling iron and which in turn may be contained in a pressing board cover which is designed to act as a carrying case for the collapsed pressing board.

Another object of this invention is to provide a telescoping pressing board which is adapted to be supported at one end so as to permit free access to the underside of the pressing surface throughout its entire length so that ladies' skirts or other similar tubular garments may be readily pressed thereon.

The invention contemplates an apparatus having two or more telescoping members which, when extended and placed in side-by-side relationship provide a planar pressing surface, one member being adapted to telescope beneath another member, guideways being provided on the other member to guide the smaller member into the telescoped relationship. Supporting means for the pressing board are fixed below the guideways provided on the larger of the two members. In addition to the vertical supports associated with the supporting structure, horizontally extending footing members may be affixed to the upright supporting members having telescoping sections which, when extended, are substantially coextensive with the extended planar pressing surface. The various details of the invention in several forms will be described more fully in connection with the drawings wherein:

Fig. 1 is a side view, partly in section, of one form of the invention in the fully extended position;

Fig. 2 is a view of the underside of the device taken along the line 2—2 in Fig. 1, with parts cut away;

2

Fig. 3 is a side view, of the form shown in Fig. 1, in the collapsed or telescoped position;

Fig. 4 is a sectional end view taken along the line 4—4 in Fig. 3, with parts cut away;

Fig. 5 is a perspective view of one form of cover for the pressing surface;

Fig. 6 is a perspective view of the form of the invention shown in Figs. 1—4, positioned for encasement in an alternate form of pressing cover 10 which may be alternately utilized as a carrying case for the device;

Fig. 7 is a perspective view of an alternate form of the invention;

Fig. 8 is a perspective view of a detachable iron supporting member for assembly with the device shown in Figs. 1—4 and 6;

Figs. 9 and 10 are perspective views showing alternate types of supporting structures; Fig. 9 also shows a sleeve pressing board extension; and

Fig. 11 is a side view of the form of invention shown in Fig. 7.

Referring to Figs. 1—4 and 6 showing one form of the invention, the planar pressing surface is formed by members 10, 11 and 12 which may be made of any suitable thin lightweight material, such as sheet metal. The member 10 has a flat upper surface 13, which is in part defined by parallel edges 14 and a transverse edge 16 which is at right angles to the parallel edges 14. Skirt portions 17 depend from the parallel side edges 14 and are provided with return ledges 18 which are parallel to and beneath the underside of the flat surface 13.

Member 11 has a flat upper surface 21 which is defined by parallel edges 22. The distance between the parallel edges of the surface 21 is slightly less than between the parallel edges 14 of the flat surface 13. The lengthwise dimension of the flat surface 21 is defined by the transverse edges 24 and 25 which are parallel to each other and which are at right angles to the longitudinal parallel edges 22. Skirt portions 26 depend from the longitudinal parallel edges 22.

Member 12 includes a flat upper surface 28 having a straight transverse edge 29 and two longitudinal edges 30 which are parallel to each other and at right angles to the transverse edge 29, adjacent the said edge 29 and for a portion of their length. However, the edges 30 gradually converge to define a curved end portion 32 of the flat upper surface 28. The width of the flat surface 28 between the longitudinal edges 30 is somewhat less than the width of the flat surface 21 of the member 11. Skirt portions 33 depend from the longitudinal edges 30 of the member 12. The skirt portions 17 are provided with grooved

guideways 35. The member 11 is provided with a plate 37 fixed, by suitable means, such as welding, to the underside of the flat surface 21 adjacent the transverse edge 24 and extending outwardly therefrom and parallel to the flat member surface 21. Projections 38 extend outwardly from the ends of the plate 37 (as shown in Figs. 2 and 4) and are adapted to be received in the grooved guideways 35 of the member 10. The guideways 35 are provided with a lower track which extends the length of the skirt portions 17, a short parallel upper track 41 adjacent the transverse edge 16, and a connecting track 42 between said upper and lower tracks. The projections 38 are adapted to move along the lower track when the member 11 is moved out of telescoping relation with the member 10 and is shifted to the upper track 41 through the connecting track 42 to position the upper surface 21 of member 11 in a co-planar relationship with the upper surface 13 of member 10, the transverse edges 16 and 24 of the respective flat surfaces 13 and 21 being in abutting side-by-side relationship and the member 37 bearing against the underside of the surface 13 to provide a rigid support between the members 10 and 11. When the member 11 is in the telescoping relation to the member 10, i. e. with the projections 38 moving along the lower track of the guideway 35, the lower edges 43 of the skirt portions 26 are supported on the ledges 19 which are provided on the skirt portions 17.

The member 12 is adapted to be telescoped within the member 11 in the same manner that the member 11 was telescoped within the member 10. That is to say, the guideways 45 are provided upon the inner surface of the skirt portions 26. Projections 47 are provided on the ends of the plate member 49 which is affixed to the underside of the flat surface 28. The projections 47 are received in the grooved guideways 45.

The plate member 49 is fixed adjacent the transverse edge 29 and extends outwardly and parallel to the flat surface 28. When the member 12 is moved outwardly from the telescoping relation with member 11 and the projections 47 are moved along the lower track of the guideways 45 through the connecting track 52 and back along the upper track 51, the transverse edges 25 and 29 of the respective flat surfaces 21 and 28 are brought into abutting side-by-side relationship to each other, the upper surface of the extension of the plate 49 is in contact with the underside of the surface 21 to provide a rigid connection between the members 11 and 12.

A supporting structure designated generally as 53 includes parallel arms 54 fixed respectively to the undersides of the ledges 19 on the skirt portions 17 of the member 10. The parallel arms 54 curve downwardly to define two upright supporting members 56 which may be of any desired height depending upon the manner in which it is determined to use the pressing board. In the form shown in the figures, the supporting members 56 are relatively short so as to add to the compactness of the device. In this form it is contemplated that the pressing board will be placed upon the broad surface of a piece of furniture to bring the pressing surface to a suitable height for convenient use.

The upright supporting members 56, in turn, curve inwardly to form suitable footing members 58 which are adapted to rest upon the floor or the top of a piece of furniture, depending upon the height of the upright supporting members 56.

The footing members 58 are substantially parallel to each other and also parallel to the arms 54 and the planar pressing surface formed by the flat surface of members 10, 11 and 12. The footing members 58 are provided with telescoping extension arms 60 and these in turn are provided with additional telescoping parallel extension arms 63 joined at their outer ends by transverse arm 62. The supporting structure is formed of tubular members and the telescoping extensions are also tubular in form. The telescoping extensions 60 are provided with projections 65 which are slidably disposed in slots 66 provided in the footing members 58. The outer surfaces of the extensions 60 slidably engage the inner surfaces 61 of the members 58. The projections 65 in the slots 66 prevent the complete withdrawal of the said extensions 60. Projections 64 on the arms 63 are slidably disposed in slots 59 provided in the extension members 60 to prevent the withdrawal of the arms 63 from the members 60.

When the members 11 and 12 are telescoped within the member 10 and the extension arms 60, 63 are telescoped within the footing members 58, as shown in Figs. 3, 4 and 6, it will be appreciated that the pressing board occupies a materially reduced space than the ordinary type of rigid board. In order to extend the board and the supporting structure for use, the operator may grasp the transverse arm 62 and draw it out until the extension members are in their fully extended position, as shown in Figs. 1 and 2. Thereafter, the member 11 is pulled outwardly from the member 10, and, when the projections 38 moving in the lower tracks of the guideways 35 reach the end of said tracks, adjacent the transverse edge 16 of the member 10, the operator lifts the member 11 upwardly so that the projections 38 move along the connecting tracks 42 to raise the surface 21 into co-planar relationship with the surface 13. Thereafter, the operator pushes the member 11 toward the member 10 so that the projections 38 move backwardly along the tracks 41 causing the transverse edges 16 and 24 to be brought into abutting relation and to bring the supporting plate into position on the underside of the surface 13. Thereafter, the member 12 is moved outwardly so as to be positioned in co-planar relationship with the other two members in the same manner as member 11 was moved into abutting co-planar relationship with the member 10. Suitable locking means may be provided to maintain the transverse edges of the respective members from moving out of abutting relationship once they have been placed in such position. One practical locking means may be provided by the ironing board cover, as will be more fully discussed below.

The perforations 68 provided in the flat surfaces of the members 10, 11 and 12 are to permit the escape of steam from the ironing surface when the board is in use.

With the supporting structure in the extended position, it will be noted that the footing members and their associated extensions are substantially coextensive with the pressing surface and thereby provide a cantilever supporting means for the pressing surface, which is particularly desirable for it leaves the entire underside of the pressing surface unobstructed, so that the skirts and other similar garments may be slipped over the ironing board and drawn the full length thereon.

It is contemplated that the pressing surface 75 will be covered with an ironing cover of suitable

fabric. A type of ironing cover which has been found particularly desirable is illustrated in Fig. 6. The cover 69 may be of padded muslin or other material, and, as shown, is adapted to serve the dual purpose of a pressing cover for use with the extended pressing surface formed by the members 10, 11 and 12, and also as a carrying kit for the pressing board when it is in its collapsed condition. The portion 70 of the cover is in the form of an envelope closed at the end 74 and along the sides 86 and having an opening adjacent the end 76. The portion 70 is adapted to be slipped over the pressing surface of the extended members 10, 11 and 12 to envelop the top and bottom surfaces of the board. The flap portions 71 and 72 are adapted to be drawn around the underside of the pressing surface, and to be clasped together to retain the cover in position on the board. Fastening means such as snap fasteners 75, may be provided on both sides of the open end 76 of the ironing cover to close the envelope 70 over the end of the board remote from the curved end so as to maintain the cover in a stretched condition on the board.

When it is desired to enclose the collapsed pressing board in the ironing cover, the board is placed upon the pressing surface of the ironing cover in central position, as shown in Fig. 6, and the flaps 71 and 72 folded up and around the upper surface 13 of the member 10, the flaps being maintained in the folded position by the complementary snap fasteners 78 and 79. Thereafter the end 76 is drawn over the fastened flaps 71 and 72 and the end 74 is folded upon the end 76. The ends 74 and 76 are maintained in the folded position by the complementary snap fasteners 80 and 81. The gussets 82 between the several flaps may be folded inwardly as the flaps or end portions are folded into position so as to close the corners of the kit. The cover, therefore, forms a neat travelling case for containing the pressing board. It may be found desirable to cover the outer surface of the pressing cover with a plastic material, leather, or other suitable wear-resistant or decorative fabric to enhance the appearance of the kit formed by the cover 69.

Fig. 5 illustrates an alternative form of ironing or pressing cover to be utilized with the several forms of the invention and is shown in use in Fig. 1. It consists of a complete envelope 125 which, as shown in Fig. 1, is adapted to be slipped over the upper and lower surfaces of the pressing board being drawn over the outer rounded end 32 of the pressing board and brought up to the end 77 adjacent the supporting structure. Suitable fastening means, such as complementary snap fasteners 126, may be provided to secure the cover in place.

It will be noted that the pressing covers 69 and 125, shown respectively in Figs. 6 and 5, are drawn over the curved end of the pressing board and are joined at the other end of the board so that the cover is stretched tightly over the pressing surface. In addition to serving adequately as pressing covers, they also provide effective locking means to prevent the several members which form the pressing surface from moving out of abutment with each other while the board is in use, and thus to lock the projections on the members in the upper tracks of their respective guideways.

It may be found useful to provide a detachable metal plate such as the plate 83, shown in Fig. 8, which has a flat central portion 84 and curved

clamping portions 85 to engage the tubular footings members 58 so as to form a rigid lower surface for the pressing board when it is in the collapsed position ready for travelling. The space 5 between the flat portion of the plate 83 and the undersurface of the telescoped member 12 may then be utilized as a storage space for a travelling iron or other related accessories. When the pressing surface is in use, the plate member 83 may be detached from the footing members 58 and inverted, as shown in Fig. 8, for use as an iron stand.

Figs. 7 and 11 illustrate an alternative form of the invention. The members 90, 91 and 92 form the pressing surface for the device and are adapted to be telescopically interfitting and in the same manner as the form described in Figs. 1-4 and 6 or in any other suitable manner which will provide a means for moving the members into 15 abutting side-by-side relationship to form a substantially planar pressing surface. In addition to the telescoping arrangement, the member 90 in this form of the invention is provided with a flat lower surface 93 parallel to and below the 20 upper flat pressing surface of the member 90, the surface 93 being connected to the pressing surface of member 90 by skirt portions 95. The height of the compartment formed by the upper and lower 25 surfaces of the member 90 is sufficient to permit the storage of a folding type travelling iron such as illustrated at 97 which is provided with a folding 30 handle 98.

Suitable supporting means may be provided under the extended portion of the device shown 35 in Figs. 7 and 11. Such supporting means may be an integral extension from the skirt of the curved end 99 or may be a folding leg extending from the underside of member 91 or 92. The 40 form of supporting means, illustrated in Figs. 7 and 11, is a pivotally mounted removable supporting member 100 adapted to be positioned in the hole 101 provided in the end 99 of the member 92 shown in dotted line in Fig. 7 and full line in Fig. 11. The supporting member 100 is provided 45 with a hook 102 adapted to engage and maintain the member in the hole. The top 103 of the hook member may be slightly flattened or otherwise formed to provide an adequate bearing surface against the hole when the member is in supporting 50 position. An enlarged foot portion 104 may be provided at the end of the supporting member 100 to give greater stability to the support. The pivotal form of supporting member is desirable 55 because it may be displaced easily to permit the insertion or removal of part of a garment such as a skirt under the pressing board. The supporting member returns to its vertical upright supporting position after the passage of the garment and provides adequate support whether 60 a garment is beneath the pressing board or not.

An alternate or supplemental means of supporting the board and retaining it in position is to provide clamp means extending from the member 90 and adapted to engage the underside of the 65 edge of a table or other piece of furniture.

As suggested above, other supporting means 70 may be substituted for the member 100. A suitable position for such substitute supporting means would be adjacent the juncture of the members 91 and 92 to thereby leave the round end 99 of the member 92 free of obstruction.

Fig. 10 illustrates an alternate form of supporting structure to be used in conjunction with 75 a collapsible ironing surface of the types illus-

trated in Figs. 1-4 and 6. It is contemplated that such a supporting structure will be utilized in a more or less permanent location, such as in the kitchen or bathroom, wherein it is desirable to have a collapsible ironing board. The supporting structure comprised of parallel arms 116 is adapted to be affixed in a suitable manner, such as by riveting or welding to the underside of the return ledges 112, the parallel horizontal arms 110 curving to form upright supporting arms 114. The arms 114 are adapted to be received in suitable wall brackets 116 having collars 118. When it is desired to use the device, which is supported by such a wall bracket, the pressing surface shown in part at 123 is constructed and extended in the manner described with regard to Figs. 1-4 and 6. When not in use, the portions of the pressing surface are telescopically interfitting with each other so that the only portion of the pressing surface extending out from the wall is the flat surface of member 120, corresponding to member 10 in Figs. 1-4 and 6. This flat surface may be utilized as a small shelf, if desired, or the pressing surface may be withdrawn from the collars 118 of the wall brackets 116 by lifting the pressing surface members upwardly to remove the upright supporting arms 114 from the collars. In order to make the collapsed pressing surface more compact, the parallel arms 110 may be so mounted on the underside of the guideways 112 so as to permit a limited rotation thereof about the cylindrical axes of said parallel arms so that the upright supporting members are brought into a plane substantially parallel to the flat pressing surface 120. A standard bayonet-type of locking means may be provided to achieve the desired limited rotational arrangement.

Fig. 9 illustrates a modified form of the device shown in Figs. 1-4 and 6. The members 130, 131 and 132 form a pressing surface when fully extended in the same manner as the members 10, 11 and 12 of Figs. 1-4 and 6. An additional extension member 133 is provided as a sleeve pressing board which telescopes within the member 132. A slot 134 is provided in the outer curved end 135 of member 132. The member 133 is supported on parallel guideways 136 consisting of ledges depending from the underside of member 132. A plate 137 may be affixed to the upper surface of the member 133 adjacent its inner end, which abuts against the inner side of the curved end 135 of the member 132. The upper face of plate 137 bears against the underside of the member 132 to provide suitable rigidity for the member 133 when it is in the extended position shown in Fig. 9. The pressing cover which is used with the pressing board shown in Fig. 9 may be provided with a slot, corresponding to the slot 134 in the curved end 135 of the board, to permit access to the sleeve board 133.

The supporting members 132 may be provided with telescoping extensions similar to those shown in Figs. 1-4 and 6. However, the supporting members 130 may be rotatably attached to the underside of the ledges 139 by means of collars 140 so that the members 130 may be folded upward when not in use. Suitable locking means may be provided to maintain the legs in the open and folded positions.

It will be appreciated that the several forms of the invention described herein are merely illustrative and that the structure and the arrangement of parts may be changed or modified without departing from the scope of the invention.

What is claimed is:

1. A telescoping pressing surface comprising at least two members having relatively thin flat surfaces adapted to be assembled in co-planar side-by-side relationship to provide a pressing surface, the flat surface of the first member being defined in part by parallel edges and a transverse edge at right angles thereto, the flat surface of the second member being defined in part by parallel edges slightly closer together than those of the first member and a transverse edge at right angles thereto, said transverse edge of the flat surface of the second member being adapted to abut the transverse edge of the first member, skirt portions depending from the parallel edges of the first member and having guideways provided therein, a plate member affixed to the underside of the flat surface of the second member adjacent the transverse abutting edge of said second member and extending outwardly therefrom parallel to the flat surfaces of said first and second members, projecting guide means provided on said plate member extending outwardly therefrom at right angles to the parallel edges of said second member, the guide means provided on said plate member being adapted to engage the guideways on the skirt portions of the first member, each of said guideways including a lower track extending parallel to the flat surface of said first member substantially the length of said member and an upper track parallel to said lower track and spaced therefrom, said upper track extending from a point adjacent the transverse edge of the first member a short distance inwardly along said skirt, a connecting track between said upper and lower tracks adjacent the transverse edge of the first member, the guide means on said plate being adapted to move along the lower track of each of said guideways through the connecting track and into the upper track to position the second member in co-planar side-by-side abutting relationship with the flat surface of the first member, a pressing cover comprising an envelope closed at one end and along its sides and open at its other end and adapted to be drawn over the outer end of the flat surface of the second member and having fastening means at the open lips of the cover which may be drawn over the end of the flat surface of the first member remote from the abutting edges of said two members to securely fasten the cover on said pressing surface and to prevent the guide means associated with the second member from moving out of the upper tracks of the guideways, and support means adapted to support the pressing surface.

2. A telescoping pressing surface comprising at least two members having relatively thin flat surfaces adapted to be assembled in co-planar side-by-side relationship to provide a pressing surface, the flat surface of the first member being defined in part by parallel edges and a transverse edge at right angles thereto, the flat surface of the second member being defined in part by parallel edges slightly closer together than those of the first member and a transverse edge at right angles thereto, said transverse edge of the flat surface of the second member being adapted to abut the transverse edge of the first member, skirt portions depending from the parallel edges of the first member and having guideways provided therein, a plate member affixed to the underside of the flat surface of the second member adjacent the transverse abutting edge

of said second member and extending outwardly therefrom parallel to the flat surfaces of said first and second members, projecting guide means provided on said plate member extending outwardly therefrom at right angles to the parallel edges of said second member, the guide means provided on said plate member being adapted to engage the guideways on the skirt portions of the first member, each of said guideways including a lower track extending parallel to the flat surface of said first member substantially the length of said member and an upper track parallel to said lower track and spaced therefrom, said upper track extending from a point adjacent the transverse edge of the first member a short distance inwardly along said skirt, a connecting track between said upper and lower tracks adjacent the transverse edge of the first member, the guide means on said plate being adapted to move along the lower tracks of each of said guideways through the connecting track and into the upper track to position the

second member in co-planar side-by-side abutting relationship with the flat surface of the first member, and releasable holding means for maintaining the two members in side-by-side relationship along their respective transverse edges.

JOSEPHINE S. BUCHANAN.
